UNITED STATES PATENT OFFICE

NELSON T. BRANCHE, OF TOLEDO, OHIO, ASSIGNOR TO SURFACE COMBUSTION CORPORATION, OF TOLEDO, OHIO, A CORPORATION OF NEW YORK

VALVE OPERATING MECHANISM

Application filed July 26, 1929. Serial No. 381,142.

This invention relates to valve operating mechanism and has for its object to provide an improved power-operated snap-action valve that shall be simple in construction and reliable in operation. The invention has special utility in connection with gas burning apparatus adapted for use with domestic house heating furnaces but is not limited in its application to such use.

10 In the accompanying drawings wherein the preferred embodiment of the invention is shown:

Fig. 1 shows the improved valve mechanism associated with a gas burning apparatus a portion only of the latter being shown, and

Fig. 2 is a section through the improved apparatus.

Referring to the drawings, 5 represents a 20 box-like conduit forming part of a gas burning apparatus provided with a damper 6 for the admission of secondary air to the gas burner (not shown), the combustible mixture supply pipe for the burner being indicated at 7, gas being delivered to this pipe from the gas valve generally indicated at 8 and air for mixing with the gas being controlled by a shutter 9 at the front of the conduit, said front being closed by a body 10 having formed 25 therein appropriate passages for delivering the air and gas to said pipe which at its forward end constitutes a mixing tube. The burner apparatus itself forms no part of the present invention but has been briefly described to indicate the environment where the invention finds special utility.

The gas valve is either fully open or closed depending on heat requirements. When the gas valve is open, the secondary air damper 6 40 is also open and vice versa, appropriate connections being provided between the damper and valve operating mechanism to effect this result. Said connection preferably comprises a lever 11 one end of which is connected to the damper by a spring 12 and the other end 45 of which is pivoted to a vertically movable operating shaft or rod 13 forming part of the gas valve operating mechanism, the lever, when said rod is in its lowermost position, having fulcrum support on the valve body as

indicated at 14 and, when the rod is at its uppermost position, having fulcrum support on the top of the conduit 5 at the point indicated by reference numeral 15. At its fulcruming points the lever is provided with transversely adjustable abutment screws 16. The lever arrangement is such that on the initial upward movement of the rod 13 the damper is given an initial quick opening and as the rod continues to rise the fulcrum shifts to the damper-end of the lever and hence further opening of the damper is at a relatively slower speed. When the rod 13 is retracted the damper movement is of course just the reverse of that stated. The advantage of this arrangement will more fully appear herein-after.

It will be noted from Fig. 2 that the valve chamber is relatively long. The gas inlet is indicated at 17 in Fig. 1 and the gas outlet 70 at 18 in Fig. 2, communication between the two being through the usual valve-controlled passage, the valve being indicated at 19. The valve 19 is appropriately mounted and confined on a valve stem 20 which in turn is appropriately confined for axial movement as will be readily understood.

The rod 13 previously referred to extends 75 into the valve chamber through a gas tight packing 21 and beyond the limits of the valve chamber proper through an appropriate opening in the lower wall of the chamber, said opening being closed by a cup-like receptacle 22 having a flange for securement to 80 the valve chamber wall as is clearly shown in Fig. 2.

Positioned within the receptacle 22 is a cup-like bellows 23 the upper edge of which is fixedly secured to the upper edge of said receptacle in a manner to make a fluid tight fit. The rod 13 at its lower end abuts the bottom 90 of the bellows 23. Bridging the chamber opening through which the rod 13 extends into the bellows is a spider through the hub 24 of which the rod is freely movable. A spring 25 confined between the hub 24 and a ring 26 secured on the rod serves to hold the lower end of said rod in contact with the bottom of the bellows. Extending laterally 95 and upwardly from the receptacle 22 from the

bottom thereof is a tube 27 the top of which is closed.

The receptacle 22 forms a container for liquid which of course surrounds the bellows 5 and extends up into the tube 27 to the same level as in the receptacle, the liquid filling the receptacle. This liquid may be alcohol or any other suitable liquid which will expand when heated. Surrounding the tube 27 is 10 an electric heating element 28 the leads of which are indicated at 29. It will now be understood that when the liquid which extends up into the tube 27 is heated, the pressure on the liquid will cause the bellows to 15 yield upwardly and thus cause the rod 13 to move upwardly and that when the liquid is cooled to normal the rod will move downwardly with the bellows.

Delivery of current to the heating element 20 28 will be controlled by appropriate mechanism such as a room thermostat. Thus when the room thermostat calls for heat, current will flow to the heating element and when it does not call for heat the current will be cut 25 off. When the rod rises under the influence of fluid pressure below the bellows, it will open the damper 6 as aforesaid.

The means whereby the rod 13 actuates the gas valve 19 will next be described. 30 indicates a lever or link which at one end is pivoted to the rod 13 and which at its other end straddles the valve stem 20 between two flanges or shoulders 31 formed thereon below the valve 19, both ends of said lever being 35 bifurcated as will be readily understood. A tension spring 32 anchored at one end to the chamber wall as indicated at 33 and at its other end to the lever 30 between the ends of the latter as indicated at 34 tends to close 40 the valve when the rod end of the lever is below the spring and tends to open said valve when said end is above the spring, the opening and closing of the valve taking place with a snap as will now be readily understood.

45 The generation of pressure in the receptacle 22 due to heating of the liquid in the tube 28 sufficiently to cause the bellows to move upward against the tension of the spring 32 is not instantaneous but on the contrary requires a time interval of minutes. While the bellows is gradually moving upwardly, the rod 13 actuates the damper lever 11 to open the damper and secondary air for the burner is therefore available as soon as 50 the valve 19 has been opened. Conversely the damper starts to close before the gas valve can be closed and hence the burner will become extinguished very quietly. This quiet extinguishment of the burner reduces to a 55 minimum any tendency of the pilot burner to blow out as will be readily understood by those skilled in the art.

60 It may be noted that by causing the interior of the bellows to be exposed to the gas supply in the valve chamber, cooling of the

expansile fluid in the receptacle 22 is materially hastened once the heating element is non-operative.

In case the electric current should fail, the rod 13 may be elevated by hand to open the valve and be held in elevated position by a latch 35 on the rod adapted to engage a rest 36 on a post 37. When the current again comes on the rod will be moved upwardly enough to release the latch whereupon the apparatus functions as already described.

The present invention provides a simple and compact power operated valve mechanism wherein the moving parts are reduced to a minimum and which may be built at 80 relatively low cost.

What is claimed is:

1. In combination, a body forming a chamber having an inlet and outlet, a valve for controlling the passage between said inlet and outlet, a bellows the interior of which is in direct communication with said chamber, a container forming with the exterior of the bellows a sealed chamber for heat-expansible fluid, a circuit for heating the fluid, 90 mechanism connected to said valve and adapted to actuate the same in opposite directions, and means actuated by the bellows for actuating said mechanism.

2. In combination, a body forming a chamber having an inlet and outlet, a valve for controlling the passage between said inlet and outlet, a heat motor secured to said body and comprising a bellows and a surrounding container forming between them a sealed chamber for fluid, a rod normally movable with said bellows and projecting outside of said body, mechanism actuated by said rod for actuating the valve in opposite directions, and means normally inoperative but adapted to hold said rod out of operative engagement with the bellows.

In testimony whereof I affix my signature.
NELSON T. BRANCHE.
